UNITED STATES PATENT OFFICE.

FRANK L. DODGSON, OF ROCHESTER, NEW YORK, ASSIGNOR TO GENERAL RAILWAY SIGNAL COMPANY, OF ROCHESTER, NEW YORK.

TRAIN CONTROL.

Application filed January 28, 1924, Serial No. 689,020. Renewed July 30, 1927.

This invention relates to train control systems, and more particularly to means for stimulating the vigilance of the engineer and his obedience to the wayside signals, and for 5 inflicting a penalty if the engineer does not manually apply the brakes before the speed of the train is excessive.

In applying automatic train control apparatus to railroads it is considered desirable to employ such apparatus as an additional safeguard over that obtainable by a careful, alert and prudent engineer rather than as a substitute for such engineer. In other words, it is desirable to have the safety 10 of the train depend on both the automatic train control apparatus and the engineer, rather than either of these two standing alone. Also, in applying automatic train control apparatus which limits the speed of 15 the train (speed control systems) as distinguished from a system which stops the train depending alone on traffic conditions ahead (automatic stop systems) it is found difficult to determine what the safe speed at which a 20 train may run at the various points in a block is when the next block in advance is occupied, especially as the blocks are different in length, have different grades and curves, or the like.

With the above and other considerations in 25 mind it is proposed in accordance with the present invention to set up arbitrary speed limits at various points in a block which are on the side of safety, and are suitable speed limits at which all trains may safely run, even though perhaps less than the safe speed 30 limits for certain trains; and to provide means for inflicting a penalty if an automatic brake application occurs because the train passes such a point at a speed in excess of the arbitrary speed limit unless the engineer has 35 anticipated such automatic brake application by initiating a manual application. Another object and feature of the present invention 40 contemplates the provision of a simple and direct way of determining when an adequate brake application, such as the usual service application, has been effected so far as manual control is concerned, it being desirable to 45 know if an adequate brake application has been initiated and will take place, because a certain amount of time transpires between the completion of the manual control of a brake application and the brake application itself, this determination or manifestation of the 50 appropriate manual control of a brake appli-

cation continuing only so long as the manual control is undisturbed and in time will consummate the brake application. More specifically the proposed apparatus in one form includes a time element device, or clockwork 60 mechanism, which is adapted to suppress the action of a penalizing means providing the engineer has had the usual engineer's brake valve in the service brake applying position for a predetermined interval of time and has 65 not in the meantime returned the brake valve to the running or release position.

Other objects, purposes and characteristic features of the invention will appear as the description thereof progresses.

In describing the invention in detail reference will be made to the accompanying drawings in which:—

Fig. 1 shows the trackway equipment of a train control system of the continuous inductive type, a portion of the car-carried equipment being shown, and speed restricting and train performance curves of a particular block to which the present train control apparatus is applied being illustrated; 75

Fig. 2 illustrates in a diagrammatic and conventional manner the car-carried equipment of the train control system just referred to;

Fig. 3 illustrates a car-carried system similar to that shown in Fig. 2 (portions thereof being omitted) employing a modified circuit arrangement for the penalty suppressing apparatus;

Fig. 4 illustrates a car-carried system such as shown in Fig. 2 employing a modified type of penalty suppressing means which does not include a clockwork mechanism;

Fig. 5 illustrates a train control system of the inductive intermediate time-distance interval type employing a penalty suppressing arrangement including clockwork mechanism; and

Fig. 6 shows the car-carried apparatus of the system as shown in Fig. 5 including a penalty suppressing means similar to that shown in Fig. 4.

The specific embodiments of the invention as illustrated in the drawings consist of a novel arrangement for penalizing the engineer if he does not attend to his duty as applied to two distinctive types of systems, namely, (1) train control system of the continuous inductive type as illustrated in Figs. 1, 2, 3 and 4; and (2) an intermittent speed 105 110

control system of the time-distance interval type as shown in Figs. 5 and 6.

Continuous system.

5 *Trackway apparatus.*—In Fig. 1 there have been illustrated the usual track rails 1, divided by insulating joints 2 into blocks in the usual manner, only the block I and the adjacent ends of two other blocks H and J 10 being shown. Since the various blocks are the same, like parts of each block have been designated by like reference characters having distinctive exponents. Although the train control system embodying the present 15 invention may be used in connection with wayside signals of any type, such as semaphore signals, position light signals and color light signals, it has for convenience been shown applied to a system employing 20 semaphore signal Z, which have been shown conventionally without illustrating any particular form of their well-known control circuits and control mechanism.

Each of the blocks is provided with a suitable 25 source of alternating current energy at the exit end thereof, illustrated as a track transformer 3, and a suitable track relay 4 at its entrance end. This forms the well-known closed track circuit which needs no further 30 discussion.

In addition to the usual track circuit current flowing in the rails of a block, there is provided a circuit to permit the flow of alternating current in the two rails in multiple in 35 the same direction, which for convenience will hereinafter be referred to as the simplex circuit. In order to permit the flow of current in this simplex circuit, including in multiple the rails of a portion of a block or the 40 rails of the entire block, three balancing resistances 5, 6 and 7 are bridged across the rails at the entrance, at an intermediate point, and at the exit end of each block respectively. In order to supply alternating current energy 45 to these two circuits, a transmission line including wires 8 is strung along the track, the energy for the simplex circuit of each block being supplied by the transformer 9.

In order to cause the simplex current to 50 flow in one particular direction as compared with the direction of flow of the loop circuit or track circuit current along the entire length of the block at one time, and cause it to flow in the opposite direction through a 55 portion of the block only at other times, front contacts, as 12¹ and 13¹, operated by the track relay of the block next in advance, as 4¹, are provided. Referring to the block I, by looking at the circuits governed by these 60 two front contacts 12¹ and 13¹, it is readily apparent that if the track relay 4¹ is in its normal energized condition, current is permitted to flow through the two rails in multiple in the block I from the middle point of the balancing resistance 7 to the middle point

of the balancing resistance 5, and that when this track relay 4¹ is deenergized, current will flow in a reverse direction from the middle point of the balancing resistance 5 through the two rails in multiple to the middle point 70 of the balancing resistance 6 located at an intermediate point in the block. In practice the constants of these simplex circuits with respect to the constants of the loop circuit including the track transformer are so 75 chosen that the phase displacement between these two currents is as large as possible or practical, so that if these currents are detected by suitable apparatus on the train, that is, amplified and applied to a two element or three-position relay, this relay produces a torque in one direction or the other depending on the phase relation between these two currents and in turn on the position of contacts 12¹ and 13¹ of the track relay 80 ahead.

Influence communicating means.—On the vehicle, which has been conventionally shown by axles 15 and wheels 16, is a pair of loop or track circuit influence receiving elements 90 LE, comprising cores 17 terminating in pole pieces 18, each having a winding or coil 19 thereon. The coils 19 are connected in series in a manner so that the voltages induced therein, due to currents flowing in the opposite direction in the two rails, are cumulative, and these coils are connected to a suitable amplifying device AL (not shown in detail) which comprises thermionic or vacuum tube amplifiers of well-known commercial or special construction. The output lead wires of this amplifying device AL are connected to the winding LR of the control relay R.

At a suitable point on the railway vehicle is 105 a simplex element SE, which comprises a long core 20 terminating in enlarged pole pieces 21 and having a coil 22 thereon for detecting the flow of simplex current in the two rails in multiple. This coil 22 is connected to the 110 input side of a similar amplifying device AS which has its output terminals connected to the other winding SR of the control relay R. It is thus apparent that, with currents flowing in the loop circuit ahead of the train 115 and in the simplex circuit under the train having a certain phase displacement, currents will be supplied by the two amplifying devices AL and AS of a similar phase relation and will cause the relay R to be operated 120 in a certain direction, and that, if one of the track currents has its relative current flow reversed, the control relay R will be operated in the opposite direction; and that, if one of these currents is eliminated or absent, the 125 relay R will assume its deenergized or biased position. This relay R is of a suitable three-position biased type, and provided with contacts 28 and 29, which control the high cam starter magnet CSH and the low cam starter 130

magnet CSL of a suitable speed restricting apparatus to be described hereinafter, the currents for energizing these two magnets being derived from a suitable source of energy such as a battery. The battery is not shown, but B designates a connection to one terminal, and C a connection to the other terminal.

- Train performance speed characteristics.—*
- 10 Directly over the block I of the trackway shown has been illustrated a solid line curve 23 which shows the permissive speeds at which the train may run without exceeding the speed limit set up by the car-carried apparatus to be described hereinafter. It will be noted that this curve has a drooping characteristic in the first part of the block I, continues as a straight line corresponding to a constant speed for a distance, and then again 15 droops until it reaches a low constant speed limit of 20 miles per hour. The first droop in the curve is caused by the high cam to be described hereinafter, and the second droop in the curve is due to the low cam. The 20 particular block I in connection with which these curves have been shown is assumed to be either a down-grade block or a block in which the braking ability of the train is poor for some other reason, and therefore requires 25 a longer distance of movement to bring the train to a certain value than the distance in which one or the other of these cams run from a maximum to a minimum speed position.
- 30 35 The dot-and-dash line 24 illustrated shows the speeds of the train at different points along the track if the brakes are applied when the train enters the block I at a speed of about 65 miles per hour. It is thus noted that, with the character of block assumed, even though the engineer does apply the brakes upon entering the block I, he will be 30 unable to stay below the permissive speed line set up by the high cam, this being shown 40 by the fact that the dot-and-dash performance curve 24 crosses solid permissive speed curve 23 at the point 25. Also, if the engineer releases the brakes when he gets below 40 miles per hour limit, and proceeds at a 45 constant speed until he reaches the point X in the block, he will not be able to stay below the permissive speed curve enforced by the low cam, even though he applies the brakes when passing the point X, as illustrated by 50 the fact that the dot-and-dash performance curve 24 crosses the solid permissive speed curve 23 at the point 26. The continuation of the first droop in the dot-and-dash line 24 has been shown by a dotted line 27 which 55 illustrates the speed at the various points in the block that the train assumes if the brake application is continued, that is, shows the 60 brake performance curve for a complete stop from high speed. It should be understood 65 that the particular speed-distance curves

illustrated apply only to the particular set of conditions which have been assumed in order to bring out certain advantageous features of the present invention, and that these curves are not necessarily characteristic of 70 train performances for all trains in all blocks or portions of the railroad. The speed-distance curves of permissive speed and train performances are merely typical and are not intended to be accurately shown, being susceptible to wide variation in practice to conform with the different speed limits required for different kinds of equipment and varying 75 practices on railroads.

Car-carried apparatus of Fig. 2. 80

Permissive and actual speed mechanism.— Since the high cam and low cam operating mechanisms are substantially the same, except as to the particular shape of the cam and 85 the speed limit enforced, the high cam and its associated mechanism only has been illustrated. The influence communicating apparatus for controlling both the high and the low cam has already been referred to, and is 90 shown in Fig. 1, the cam starter magnet CSH of this apparatus being shown in Fig. 2. On the vehicle 15—16 is a shaft 30 driven by the wheels of the vehicle in a suitable manner. On this shaft 30 is a worm 31 meshing with a 95 worm wheel 32 which through reduction gears 33 and 34 drives a pinion 35 pivotally secured in the bifurcated end of an arm 36 which is 100 pivoted about the axis of the gear 34, so that the pinion 35 may be moved into or out of engagement with a mutilated gear 37 without disturbing its meshed relation with the gear 34. This gear 37 is pinned to a cam shaft 38 having a cam 39 fixed thereon. The arm 36 is urged upwardly by a compression spring 105 41, disposed around a guide 42, so that if the cam starter magnet CSH is deenergized the pinion 35 is urged upward into meshed relation with the mutilated gear 37, whereupon 110 movement of the vehicle along the track gradually turns the cam shaft 38 and its associated cam 39. In order to return the shaft 38 back to its normal position in the event that the cam starting magnet CSH is again energized, a gear sector 43, pivoted at 44, engages 115 a pinion 45 on the cam shaft 38; and this gear sector 43 is biased to an intermediate position by initially tensioned springs 46.

On the shaft 30 is mounted a centrifugal speed-responsive device G of usual and well-known construction, which comprises a collar 47 pinned to the shaft 30, another similar but grooved collar 48 slidably mounted on this shaft, these collars being coupled together by links 49 having a weight 50 at their pivotal junction, and a compression coil spring 51 between these collars.

Parallel and preferably adjacent to the shaft 38 is a speed shaft 53 to which is pinned 120 a bifurcated arm 54 engaging the groove in 125

130

the collar 48. Pinned to this shaft 53 is a speed arm 55 and a speed cam 56. An increase in the speed of the shaft 30 causes the collar 48 to move in response to the centrifugal force acting on the weights 50 in opposition to the spring 51, so that the speed shaft 53 and speed arm 55 and the speed cam 56 are moved in a clockwise direction. To the lower and free end of the speed arm 55 is pivotally secured one end of a floating lever 57 which carries a roller at its other end engaging the cam surface of the cam 39. At an intermediate point on the floating lever 57 is pivotally secured one end of a link 58 which has its other end pivotally secured to an eccentrically located pin on the sector 59, which sector is pivotally supported on a pin 60. Adjacent the sector 59 is secured a spring finger 61 which has a roller 62 pivotally secured there-
 10 to which rides on the cam surface of the sector 59. This spring finger 61 normally co-
 operates with a stationary finger 63 to control a suitable circuit more clearly described hereinafter. Adjacent to the speed cam 56
 15 are provided similar contacts 64 and 65 which cooperate with this cam 56.

By looking at this structure it will be readily understood that the sector 59 will move in a clockwise direction in response to
 20 movement of the cam 39 from its normal position. It will also appear that this sector 59 moves in the same or clockwise direction in response to an increase in the speed as indicated by the governor G, so that either an in-
 25 crease in speed or movement of the cam 49 from its normal position tends to move the sector 59 in the same direction and eventually allows the roller 62 to ride into the contracted or reduced portion of this sector, thereby opening the contacts 61-63. In other words, after the cam 39 moves from its normal position, the speed of the train must be correspondingly reduced to avoid opening of these contacts. Also, it will be noted that
 30 decreasing the speed of the train to a certain value, assumed to be two miles per hour, causes the cam 56 to close a circuit at the contacts 64 and 65 for reasons more clearly described hereinafter.

Brake applying device.—The present train control system assumes the provision of means to automatically apply the brakes of the train under certain conditions of the car-
 35 carried apparatus. In order to accomplish such a brake application, a brake applying device has been illustrated conventionally by the electro-pneumatic valve EPV. This device EPV may vent the brake pipe directly, may operate a suitable engineer's brake valve
 40 actuating means, or may control a suitable pneumatically operated brake applying device which vents the brake pipe to a predetermined extent and at a predetermined rate. Since the applicability of any one of these various brake applying devices to the system

of the present invention will be obvious and requires no specific showing, further description of this apparatus is deemed unnecessary.

The usual engineer's brake valve has been shown conventionally, and is provided with a handle 66 and with suitable contact sectors 67, 68 and 69 which are adapted to close circuits in various positions of this valve as shown by the legends adjacent to these segments in the drawings.

75

Directly below the engineer's brake valve is found a cut-out cock or double-headed cock in the usual air brake system, which has been conventionally shown by the cock 70 which is provided with a contact sector 71 which bridges the stationary contacts 72 when this valve is open, for purposes more clearly set forth in connection with the operation of the system.

Timer or clockwork mechanism.—In order to suppress the penalty more clearly referred to hereinafter, it is desirable to close certain contacts, providing the engineer has had his brake valve in the service position for a cer-
 55 tain period of time and has not thereafter moved it to either the running or the release position, and in order to control such a contact a suitable clockwork mechanism CM has been shown. This clockwork mechanism comprises an escapement including a pallet 90

75 having headed screws 76 in opposite ends thereof which may be adjusted to change the moment of inertia of this pallet about its pivot 77, and consequently the period of os-
 80 cillation of the pallet. This pallet 75 is os-
 85 cillated by an escapement wheel 78 which is driven through a gear train as shown termi-
 90 nating with a gear 79 connected to a shaft 80
 95 through a ratchet wheel 81 and a dog 82, said
 100 dog being urged into engagement with said
 105 ratchet wheel by a spring 83. On the upper
 110 end of the shaft 80 is fixed a projecting arm
 115 having at its end a piece of insulation
 120 adapted to engage and close contacts 85 and
 125 235 when said arm is moved to its extreme
 130 position.

Pivottally mounted and loose on this shaft 80 is a gear 86 which meshes with a rack 87 connected to a piston 88 in a cylinder 89. This rack 87 and piston 88 are normally held in the extreme right hand position shown by a compression coil spring 90 within the cylinder 89. The shaft 80 is operatively connected to the gear 86 by a spiral spring 91 for one direction of movement, and is directly coupled to the shaft 80 for the other direction of movement of the gear by engagement of the pin 92, which anchors one end of the spring 91 to the shaft 80, with a pin 93 fastened in the gear 86.

125

Pressure is adapted to be applied against the piston 88 by connecting the cylinder 89 to the main reservoir pressure of the air brake system by an electrically operated valve EV. This electrically operated valve EV is of
 130

usual and well-known construction and includes two valve members 94 and 95 which are adapted to connect this cylinder to atmospheric pressure or main reservoir pressure respectively, the valve 95 normally being closed by the action of the compression coil spring 96. In the upper compartment of this valve EPV is an electro-magnet of the usual ironclad type, including an armature 97 and 10 a winding 98. If this winding 98 is energized, the valve 94 assumes the closed position and the valve 95 the open position, and main reservoir pressure flows into the cylinder 89. The flow of air pressure into the cylinder 89 moves the piston 88 to the left, thereby moving the pin 93 away from the pin 92, and simultaneously tensioning the spring 91. Under this condition of the apparatus the pallet 75 will be rocked back and forth in response to the torque on the escapement wheel 78 thereby slowly allowing the arm 84 to move in a clockwise direction and close the contacts 85 and 235 after a certain period of time, which is assumed to be about 6 or 7 seconds. This time interval, for which the clockwork mechanism CM is adjusted, is intended to correspond with the time required to vent the regular equalizing reservoir of the air-brake system through the engineer's 25 brake valve enough to cause a full service brake application, or such other application as the permissive speed limits require. If the electrically operated valve EV is again de-energized to allow the pressure to escape from cylinder 89, the spring 90 moves the rack 87 to its normal position and causes the pin 93 to engage the pin 92 and turn the shaft 80 back to its original position, this being permitted through the dog and ratchet engagement between the gear 79 and the shaft 80.

Operation.

Normal clear conditions.—Under normal clear traffic conditions both the high and the low cam assume their highest speed position which corresponds to the maximum permissive speed limit, assumed in this case to be 65 miles per hour, as shown by the curve 23 in Fig. 1. Assuming that the speed of the train is less than this value, which it is assumed to be as shown by the positions of the various devices in Fig. 2 of the drawings, the electro-pneumatic valve EPV is energized by a stick circuit which may be traced as follows:—Beginning at the terminal B of a suitable source of energy, wire 100, contacts 61 and 63, wire 101, winding of the EPV, wires 102 and 103, front contact 104 of the EPV, wire 105, back to common return wire C.

This circuit maintains the valve EPV in its normal inactive position, allowing the train to proceed in accordance with the manner in which it is governed by the engineer.

If the engineer should allow the speed of the train to exceed the maximum limit of 65 miles per hour, the action of the governor G through the speed arm 55 causes contacts 61—63 to open, thereby interrupting the stick circuit for the EPV and applying the brakes of the train. When the speed of the train has been reduced to, say, less than 2 miles per hour, the contacts 64 and 65 close, thereby closing a pick-up circuit for the EPV, comprising wire 100, contacts 61 and 63, wire 101, winding of the EPV, wires 102 and 106, contacts 65 and 64, wire 107, back to common return wire C. The completion of this circuit again picks up the EPV and this permits the engineer to release the brakes manually if he so desires. This requirement of bringing the speed down to practically a stop after exceeding the maximum speed limit, before the brakes can be released, is considered to be a penalty, and is assumed to make him more vigilant in the control of the train to avoid such a brake application and penalty.

The penalty above described for exceeding the maximum speed limit is optional; and if desired, by a rearrangement of the circuits which will be very evident, this penalty may be omitted so far as the maximum speed limit is concerned, by making the electro-pneumatic valve EPV non-stick for clear traffic conditions only by simply providing a shunt for its front contacts 104 closed so long as the main car relay or the high-cam starter magnet CSH is energized. In fact, to conform with the requirements of some railroads, it may be found expedient to omit the maximum speed limit under clear traffic conditions altogether, permitting the train to run, so far as automatic control is concerned, at any suitable speed under clear traffic conditions.

Caution condition (speed not excessive).—Let us assume that a train equipped with the car-carried apparatus shown in Figs. 1 and 2 is moving in the block H in the normal direction of traffic as indicated by the arrow, and that the block J is occupied by another train. With the block J occupied, the track relay 4¹ is deenergized, thereby causing the simplex circuit between the entrance to the block I and the point X to be reversed. Consequently, when the following train in question enters the block I, the control relay R will swing to the reverse position, thereby deenergizing the high cam starter magnet CSH, but maintaining the cam starter magnet CSL energized. The high cam 39 is thus initiated and is gradually rotated in one direction or the other, depending on whether the train is running pilot or tender first, thereby gradually reducing the permissive speed, as indicated by the curve 23 in Fig. 1. If the actual speed of the train does not exceed the permissive speed limits at any point, no automatic brake application will take ef-

fect, it being assumed for the present that the permissive speed limits as indicated by the line 23 are not exceeded.

After the train passes by the point X, no simplex current of any character can be detected, and therefore the low cam starting magnet CSL is also deenergized. This condition of the apparatus causes the low cam to be gradually turned to restrict the speed 5 of the train as indicated in the second droop of the solid line 23 (Fig. 1). If the engineer does not allow the speed of the train to exceed at any point these permissive speed limits, no automatic brake application takes 10 effect.

Caution condition; speed excessive.—The gradually decreasing permissive speed limits, indicated by the curves 23 and the solid lines in Fig. 1, are produced by movement of the 20 two cams; and since these cams are driven from the car wheels, the curves of permissive speed set up are the same for each block or control point on the railroad, whether on an up-grade or on a down-grade; and these permissive speed curves are the same for the 25 particular locomotive equipped whether running alone or pulling a long or a short train. As previously explained, there sometimes are portions of track where it is not possible for 30 all trains to keep below the permissive speed limits at all points in a caution block, unless the train is handled and braked in some unusual or peculiar manner.

In conformity with the theory of train 35 control on which this invention is based, it is desired to stimulate and enforce vigilance on the part of the engineer in obeying the indications of the block signals, particularly the caution signal. One way of maintaining 40 such vigilance is to penalize the engineer each time he allows his train to exceed the permissive speed limits arbitrarily and automatically established, it being assumed that the engineer, in order to avoid such penalty, 45 will keep vigilant and handle his train safely. Such an expedient for maintaining vigilance is found objectionable in many instances, because it is difficult for the engineer to observe the arbitrary speed limits for all blocks without special manipulation. Obviously any 50 penalty imposed should be one fair to the engineer and preferably one which the engineer can readily avoid by exercising ordinary prudence and care in the handling 55 of the train.

In view of these considerations, it is proposed in the present invention to provide a 60 penalty which the engineer may avoid in either of two ways, namely, maintaining the speed of his train at all times below the arbitrary speed limits, or prior to exceeding such arbitrary speed limit, manifesting his vigilance by initiating a brake application. It is thought that with such arrangement the 65 engineer may handle his train in the regular

way and so long as alert and vigilant may readily avoid the penalty. In order to be sure that the engineer is alert and vigilant, it is required that he must take the appropriate action before any automatic brake application or other operation occurs, otherwise the engineer might become careless and wait until he felt the brakes being applied before acting to forestall the penalty.

To facilitate the explanation of these features where a regular full service brake application initiated at the block signal or corresponding control point, at which the cam is started, will not maintain the speed of the train below the permissive speed limits, if the 70 train enters the block at its normal running maximum speed, let us assume a train, running its normal speed of about 62 miles per hour, enters the block I, and suppose for the first set of conditions that the engineer is 75 asleep, neglectful, or otherwise fails to take appropriate action in obedience to the caution signal. As the train continues at the maximum speed limit prescribed by the cam, the speed-distance contacts 61—63 open, and deenergize the electro-pneumatic valve; and since this valve is energized by a stick circuit, once deenergized, it remains deenergized until picked up by closure of contacts 64—65 at a speed of 2 miles per hour, or substantially 80 90 stop. In short, if the engineer is negligent, an automatic brake application occurs; and the train must be brought to a substantial stop before the brakes can be released and the train proceed. This constitutes the penalty 95 for lack of vigilance.

Suppose, however, that the engineer sees and recognizes the caution indication of the block signal at the entrance to the block I, and realizing the high speed at which his 100 train is traveling, moves the handle of his regular engineer's brake valve to the service position for the purpose of applying the brakes, this movement of the brake valve occurring before the permissive speed limits are 105 exceeded. So long as the engineer's brake valve is in the service position, it is obvious that the brakes are being applied at the service rate as rapidly as consistent with safety and as rapidly as can be suitably done by any 110 automatic brake applying device. In other words, the engineer's manual action tends to slow down the train as effectively as an automatic application of the brakes. The 115 engineer has manifested in this way his vigilance, and the penalty may be suppressed. It is not necessary in the interests of safety to have the brakes fully applied at the instant the permissive speed limits are exceeded, 120 since these permissive speed limits are selected and set up on the assumption that the starting of a brake application at that particular point and speed will bring the train to a stop at the desired point. Accordingly, 125 it is sufficient if the engineer gets his brake 130

valve in the service position before exceeding the speed limits, the time taken to get the brakes fully applied being no longer than that required for an automatic application, and due allowance for this time is made in determining the permissive speed limits.

Applying these principles to the specific system shown in Fig. 2, if the engineer is vigilant and puts his brake valve in the service position before the speed contacts 61-63 open, the contact fingers 114 are bridged by the segment 67, thereby completing an auxiliary stick circuit for maintaining the valve EPV energized independently of its control by the speed contacts 62-63, as follows:— Beginning at B, contacts 67-114, wires 115 and 112, contacts 71-72, wires 113 and 101, winding of the valve EPV, wires 102 and 103, front contacts 104 of the EPV and wire 105 back to the other terminal C of the battery.

It will be observed that the engineer must move his brake valve to the service position and close contacts 67-114 before the valve EPV is operated, otherwise the front contacts 104 of said valve are open and interrupt the auxiliary stick circuit above traced. Hence, the engineer cannot wait until some automatic operation occurs before acting.

In the ordinary type of air brake system contemplated by this invention, the brake pipe is vented by the action of the equalizing discharge piston valve responsive to pressure in the equalizing reservoir. The engineer's brake valve exhausts the pressure from the equalizing reservoir, and the brake pipe pressure in time assumes a corresponding pressure, the length of time required to vent the brake pipe varying with its volume, i. e. length of the train. In the ordinary brake equipment a full service application is made by about 20 pounds reduction; and the engineer may reduce the pressure in the equalizing reservoir about 20 pounds by keeping his brake valve in the service position for 6 or 7 seconds. It is unnecessary to exhaust the equalizing reservoir pressure any lower than this, otherwise there is a waste of air in blowing down the brake pipe pressure more than required to give a full service application. It frequently takes a much longer time than 6 or 7 seconds to stop the train; and to avoid this waste of air, the timing mechanism CM is employed; so that if the engineer has kept his brake valve in the service position for 6 or 7 seconds (long enough to make the desired full service reduction in the equalizing reservoir pressure) the timing mechanism will serve to maintain the valve EPV energized and the engineer may then move his brake valve out of the service position to the lap position.

When the engineer moves his brake valve to the service position to initiate the control of a service brake application, the contact fingers 110 are bridged by the contact segment

69 so as to complete a circuit for the electrically operated valve EV, which is readily traced in the drawings. With the valve EV energized, the clockwork mechanism CM is started; and after an interval of 6 or 7 seconds the contacts 85 and 235 are closed, whereupon the device EPV is maintained energized through another partial circuit entirely independent of the speed contacts 61 and 63 and the valve contacts 67-114, which may be traced as follows:—beginning at the terminal B, wire 111, contacts 85, wire 112, contacts 71-72, wires 113 and 101, winding of the EPV, wires 102-103, front contact 104, wire 105, back to the common return wire C.

Since the engineer has held the handle 66 of his brake valve in the service position for this period of time (6 or 7 seconds), the appropriate reduction in the equalizing reservoir pressure for a full service application is assumed, and he may move his engineer's valve into the lap position, the electrically operated valve EV being maintained energized through the following stick circuit:—beginning at the terminal B, wire 111, contacts 235, wire 116, contacts 68-117, wire 118, front contact 119 of the valve EV, wires 120 and 121, winding of the valve EV, wire 122 back to common return wire C.

If the engineer should attempt to defeat the objects of the invention, and instead of making a full service reduction in equalizing reservoir pressure, should move his brake valve out of the service position before the expiration of the time interval of 6 or 7 seconds, the valve EPV is deenergized, and thereafter the train must be brought to a substantial stop (2 miles per hour) before the brakes can be released, this assuming of course that the speed of the train at the time in question is above the permissive speed limit. This result follows from the fact that, as soon as the engineer moves his brake valve out of the service position, the contacts 67-114 open; and since there has not been time enough for the contacts 85 to close, both auxiliary stick circuits for the valve EPV are interrupted. Also, if the engineer should attempt to release the brakes while the speed is excessive after he has made the required full service application, the valve EPV is deenergized and the penalty imposed, because in the releasing positions of the brake valve (release or running), the contacts 67-114 are open, and likewise contacts 69-110 are open. The opening of the latter contacts 69-110 deenergizes the valve EPV and instantly restores the timing mechanism CM to the normal or initial position, opening contacts 85. Both of the auxiliary stick circuits for the valve EPV are consequently open.

The contact segments 67, 68 and 69, as shown, are of such length that they bridge their corresponding pairs of fingers in the emergency position of the engineer's brake.

valve as well as in the service position. This is optional but is done so that, if the engineer makes an emergency application for any reason instead of a service, the penalty will be suppressed just as well as if a service application has been made, it being obviously unfair to penalize the engineer for using an emergency application instead of the service if conditions warrant.

- 10 Assume that the engineer has been vigilant and has taken the appropriate actions above described in obedience to the caution signal. As soon as the speed of the train has been reduced to a value less than the permissive speed set up by the apparatus, the engineer may move his brake valve into the running or release position, releasing the brakes and proceeding at that speed, as shown by the horizontal dot-and-dash line at the point X 15 in Fig. 1, the brake control valve EPV being energized directly through the speed contacts 61—63. Since the second low speed cam is initiated at the point X, the engineer is required to again initiate a manual brake application before the permissive speed is exceeded, which under the assumed condition occurs at the point 26, and he will be required to hold the manual brake application until the speed of the train has been reduced to less 20 than 20 miles per hour, for instance, in order to avoid an automatic brake application and the associated penalty, after which the brakes may be released and the train continue to move into the danger block at this 25 limited speed.

- 40 *Danger condition.*—When the train enters the block J assumed to be occupied by another train, the loop circuit influence receiving coils 19 will be deprived of trackway energy and the control relay R will assume its deenergized position regardless of whether or not simplex circuit current is flowing in the block J, because the track or loop circuit current is shunted away from the train in question 45 by reason of the train ahead. Assume now that, with the train in question moving in the block J, the other train heretofore mentioned moves out of the block J into the following block. Under this condition the loop circuit apparatus of the train in question again receives energy from the loop circuit ahead of the train, and the simplex winding of the relay R a current of reversed relative direction of flow therein, so that the relay R again 50 assumes the reversed position and permits the train to proceed at the intermediate speed of 40 miles per hour, provided the train in question is in the rear of the point X for the block J. It is thus noted that the train control 55 apparatus may be released of its restricting control at an intermediate point in a danger block as soon as track conditions ahead become favorable, this also being true when a train moves in a caution block and such 60 block clears up in the meantime.

Modified form of speed control.—The particular organization of car apparatus shown in Figs. 1 and 2 contemplates two cams governing speeds from a high to a medium, and from a medium to a low speed, respectively. It will be evident that the scheme for imposing vigilance which characterizes this invention is not restricted to this particular form of speed control. For example, only one cam may be used, establishing speed 70 limits from an unlimited speed or a maximum down to a low or minimum. In fact, the gradual change in permissive speed limits provided by the cam or cams may be eliminated, if desired; and the system operated properly 75 with abrupt changes in speed limit from a maximum to a minimum, or from a maximum to a medium and then to a minimum speed limit.

Double-heading.—In hauling heavy trains 80 it is frequently necessary to couple two or more locomotives in the same train. Ordinarily this is done by "double-heading" that is, coupling two engines together at the head of the train. The air brake equipment for locomotives of the usual type is such that, when two locomotives are coupled together in a train, it is necessary for well-known reasons to close a valve between the main engineer's brake valve and the brake pipe, commonly 85 called the double-heading cock, on the second or other locomotive in the train in order that the brakes on this helper locomotive may be applied and released from the leading locomotive the same as if the helper locomotive 90 was a car. On account of this double-heading cock commonly found on all engine equipment, it is possible for the engineer to cut out the automatic brake control, that is, eliminate the functions of the automatic brake 95 applying mechanism which is set into operation by the deenergization of the valve EPV. This is true whether the valve EPV controls an actuator for the regular engineer's brake valve or an additional brake applying valve, 100 inasmuch as the connections to the brake pipe should be made above the double-heading cock, otherwise the brakes will be applied on the train automatically upon exceeding the minimum speed limit, because the helper 105 locomotive is unable to pick up track or loop circuit current. In short, by closing the double-heading cock the engineer may avoid 110 the automatic application.

Referring to this invention, it will be evident that if the double-heading cock has been closed, the engineer may put his brake valve in the service position for 6 or 7 seconds without applying the brakes in so doing; yet so far as the control of the EPV heretofore described is concerned, such manipulation would serve to maintain the valve EPV energized and suppress the penalty. As previously explained, however, it is one of the principles of this invention that the engineer 115 120 125 130

should not be able to suppress the penalty except by actually applying the brakes; and to assure that the double-heading cock cannot be used, together with the manipulation 5 of the engineer's brake valve, to suppress the penalty, the double-heading cock 70 is provided with a contact segment 71 bridging contact fingers 72 only if said double-heading cock is open, these contacts being open if the 10 double-heading cock is closed. These contacts 71-72, it will be noted, are included in the auxiliary energizing circuit for the valve EPV. Consequently, if the engineer should close the double-heading cock, these contacts 15 71-72 are opened by this movement, and it is not possible for the engineer to maintain the valve EPV energized and suppress the penalty. By reason of this penalty, it is considered that the use of the double-heading 20 cock to forestall automatic brake application will be discouraged, it being much easier to make a brake application in the regular way and forestall the penalty.

25 *Modified penalty suppressing means (Fig. 3).*

In Fig. 3 has been shown a portion of the car-carried apparatus of a system, such as shown in Figs. 1 and 2, in which the clock-work mechanism circuit is somewhat simplified by reason of a change in the circuit arrangement resulting from the fact that the device EPV and the valve EV have their windings connected in series at times. In this modified arrangement the electro-pneumatic 30 35 brake applying device EPV has its winding designed slightly different and is energized by a circuit such as heretofore traced in Fig. 2 which has included therein a resistance 124. This resistance 124 is substantially the same 40 as the resistance of the winding of the device EV, so that, when the device EPV is energized through resistance 124, it is supplied with substantially the same current as if energized through a circuit including the 45 winding of the valve EV and not the resistance 124.

In this penalty suppressing arrangement the device EPV is maintained energized independently of its control by the speed control mechanism when the engineer's brake valve is in the service position through the following circuit:—beginning at the terminal B, wire 125, contacts 126-127, wire 128, winding of the device EV, wire 130, contacts 50 55 71-72, wires 113 and 101, winding of the EPV, wires 102, and 103, front contact 104 of the device EPV, wire 105, back to common return wire C. The circuit just traced not only maintains the brake applying device EPV energized but also actuates the electrically operated valve EV thereby causing the contacts 85 to be closed after a predetermined time (6 or 7 seconds) by reason of the clockwork mechanism CM shown in Fig. 2.

After the contacts 85 have been closed, the 65 engineer may move his brake valve to the lap position, whereupon the devices EV and EPV are maintained energized through the following circuit:—beginning at the terminal B, wire 132, contacts 133-134, wire 135, 70 contacts 85, wires 136 and 128, through the device EV and EPV including the contacts and wires just traced. In other respects the modified circuit arrangement of Fig. 3 has the same operations, functions and features 75 as the arrangement shown in Fig. 2.

Modified penalty suppressing means (Fig. 4).

In the systems thus far described the penalty suppressing means becomes effective 80 as soon as the engineer moves the brake valve to the service position, and remains effective providing he leaves it there for at least 6 or 7 seconds. In certain railway systems it is deemed practical to require the engineer 85 to maintain the engineer's brake valve in the service position as long as the speed of the train is excessive; and in Fig. 4 has been illustrated a penalty suppressing relay PR which makes it possible for the engineer to 90 suppress or avoid the penalty providing he moves his brake valve to the service position before an automatic brake application is initiated and keeps it there.

In the system shown in Fig. 4 (portions 95 thereof being omitted) the devices used are the same as those shown in Fig. 2, except that there has been added an additional contact 138 to the brake applying device EPV, and speed contacts, comprising contact fingers 100 139, which are closed when the speed of the train is less than 22 miles per hour.

Assume that the permissive speed is gradually decreasing and the speed of the train is such that it is just about to exceed the permissive speed limit. If now the engineer moves his valve to the service or emergency position before the device EPV is deenergized, a pick-up circuit for the penalty suppressing relay PR is completed which may 105 110 be traced as follows:—beginning at the terminal B of a battery, wire 137, front contact 138 of the device EPV, wires 140 and 141, winding of the penalty suppressing relay PR, wire 142, contacts 126-127, wire 143, back to the common return wire C. With this circuit completed the relay PR picks up and completes a stick circuit through its front contact 144 which may be traced 115 as follows:—beginning at the terminal B, wire 145, front contact 144, wires 146 and 141, winding of the relay PR, wire 142, contacts 126-127, wire 143, back to the common return wire C.

If now the speed of the train exceeds the permissive speed set up by the cam 39, an automatic brake application will be initiated by the device EPV. This application may 120 125

however be ineffectual since the auxiliary reservoir has already been partially vented by manual movement of the brake valve to the service position. Even though the device EPV has assumed its deenergized position and has opened contacts 138, the penalty suppressing relay PR is nevertheless maintained energized through its stick circuit including contact 144, so long as the engineer's valve is kept in the service position. As soon as the train speed has been reduced to 22 miles per hour, contacts 139 are closed and the device EPV is picked up through the following circuit:—beginning at the terminal B, wire 100, contacts 61 and 63, wire 101, winding of the device EPV, wires 102—106 and 147, contacts 139, wire 148, contact 149, wire 150, back to common return wire C. After the device EPV is once picked up, it will again be stuck up through its stick circuit including contact 104, so long as the permissive speed set up by the cam is not exceeded.

Had the engineer put his brake valve in the service position after the brake applying device EPV was deenergized in response to excessive speed, the penalty suppressing relay PR could not have been picked up, because the pick-up circuit including the contacts 138 was not intact, and consequently a penalty would have been inflicted requiring the engineer to reduce the speed to less than 2 miles per hour before the device EPV could have again been picked up. Reducing the speed to 2 miles per hour causes closing of contacts 64 and 65 and energization of this device EPV. In other words, in the arrangement shown in Fig. 4 the engineer, if alert, may anticipate the automatic action by a partial or complete manual brake application, and by so doing is permitted to release the brakes as soon as the speed is less than 22 miles per hour; whereas if he fails to anticipate the automatic action he is penalized by being required to bring the train to a low speed of, say, 2 miles per hour which practically corresponds to a stop.

In the arrangement of Fig. 4, whenever the train exceeds the permissive speed limits, the engineer must keep his brake valve in the service position until the train has been brought down to a low speed, assumed to be 22 miles per hour. Keeping the brake valve in the service position for an extended period of time may result in an unnecessary reduction in brake pipe pressure; but in some cases and under some circumstances, this may not be objectionable, the train frequently being braked down to a speed less than a suitable control speed, such as 22 miles per hour, before the brake pipe has been materially over reduced.

Intermittent systems; description of Fig. 5.

65 *Trackway apparatus.*—The particular

type of intermittent system to which the penalty suppressing means embodying the present invention has been shown applied is one of the time-distance interval type. This system includes track elements for transmitting control influences to the car-carried apparatus of which a pair of such elements is used to transmit two successive impulses in less than a certain time if the speed of the train is excessive as determined by the spacing of such pair of elements. In order to simplify the disclosure of the system shown in Fig. 5 only one pair of a series of pairs of track elements has been illustrated, this pair being shown at the exit end of the block M, so one element of which is controlled by the track relay 4^a of the block N next in advance, the other element of this pair being permanently active.

The first element of each pair comprises a U-shaped core 152 terminating in enlarged pole pieces 153 preferably constructed of a high grade of laminated magnetic material. The second element of each pair comprises a similar core having a winding 154 thereon which is normally closed in a circuit of low resistance by the front contact 155 of a line relay 156 which is energized when the block next in advance is unoccupied.

Car-carried relays.—The car-carried apparatus shown in Fig. 5 includes a group of sensitive and quick acting relays CR, RR and BR. These relays are of the tractive armature type and include well-balanced light armatures pivotally supported about a vertical axis so as to make them immune to jars and vibrations and causes them to respond to small momentary changes in the flow of current therethrough. Since these relays may take any one of various forms as long as they are quick acting and immune to vibrations they have been shown conventionally, and are provided with contacts constructed and insulated so as to serve the purpose for which they are intended and as more clearly described in the operation of the system.

Time element device.—In order to apply the brakes of the train by the deenergization of the electro-pneumatic valve EPV when two successive control influences are received in less than a certain time, a suitable time element device is required. In the particular embodiment of the invention illustrated this time element device TE has been shown diagrammatically. This time element device essentially comprises a balance wheel 158 which is normally held in the position shown in the drawings by the time starting magnet TM in opposition to the bias of a spring 159 having its one end fastened to the shaft 160 and the other end to a pinion 161. This time element device TE is so constructed that if the timing magnet TM is momentarily deenergized the balance wheel 130

158 will move in a counter-clockwise direction through an angle of substantially 240° as shown by the dotted position of the contacts 162 and 163. If the timing magnet 5 TM was deenergized for some time, the balance wheel 158 would finally assume an intermediate position substantially 120° toward the left of the normal position. In order to restore the time element device to its 10 normal position when it assumes such an intermediate position, a suitable pneumatically operated restoring device has been provided.

15 *Time element restoring device.*—This restoring device comprises a rack 165 in engagement with a pinion 161 and adapted to be operated by a piston 166 contained in a cylinder 167 and urged to the extreme right hand position by a compression coil spring 20 168. An electrically operated device ED, which is constructed substantially identically to that of the device EV of Fig. 2, is provided to restore the time element device TE and certain other devices to their normal 25 position or condition as more clearly pointed out hereinafter.

30 *Speed responsive device.*—In connection with the train control system as shown in Fig. 5 a speed responsive device which indicates the actual running speed of the train at any time is required. In order to simplify the description of the system, a speed governor G of the same centrifugal type shown in Fig. 2 has been illustrated. This device 35 governs the position of a multiple contact speed arm 169 which is adapted to close various circuits under various existing speed conditions, as more specifically pointed out hereinafter.

40 *System under normal conditions.*—Under normal clear traffic conditions of the car-carried apparatus, the control relay CR is energized by a circuit which may be traced as follows:—Beginning at the terminal B of 45 a suitable battery, wire 170, front contact 171 of the control relay CR, wires 172 and 173, winding of the control relay CR, wire 174, secondary coil S of a car element L, wire 175, back to common return wire C. This 50 car element L comprises a U-shaped core of magnetic material similar to that of the track elements heretofore described, but arranged in inverted relation and adapted to cooperate with such track elements. With the control relay CR energized, the repeater relay RR and the brake control relay BR are maintained energized through the following two circuits:—(1) beginning at the terminal B, wire 170, front contact 171, wires 176 and 60 177, lower winding of the repeater relay RR, wires 178 and 179, front contact 180, wire 181, back to common return wire C; and (2) beginning at the terminal B, wire 170, front contact 171, wires 176 and 182, upper wind-

ing of the brake control relay BR, wire 183, 65 back to the common return wire C.

With the repeater relay RR and the brake control relay BR energized, a circuit for energizing the timing magnet TM may be traced as follows:—beginning at the terminal B, wire 184, front contacts 185 of the brake control relay BR, wires 186 and 187, winding of the timing magnet TM, wire 188, front contact 189 of the repeater relay RR, wire 181, back to common return wire C. 75

With the brake control relay BR energized and the time element device energized and in its normal position as shown, a stick circuit for this brake control relay through its lower winding may be traced as follows:— 80 beginning at the terminal B, wire 184, front contacts 185 of the brake control relay BR, wires 186 and 192, contacts 162 of the time element device, wires 193 and 194, lower winding of the brake control relay BR, wire 195, back to the common return wire C.

With the brake control relay BR in its energized position, a circuit for energizing the primary coil P of the car element L and the electro-pneumatic brake control device EPV in series may be traced as follows:—beginning at the terminal B of a suitable source of energy, wire 196, front contact 197 of the brake control relay BR, wire 198, resistance 199 (used for reasons hereinafter described), wires 200 and 201, primary coil P, wire 202, contact 203 operated by the rack 165, wire 204, winding of the device EPV, wires 205 and 206, front contact 228 of the EPV, wire 229, back to common return 100 wire C.

With the primary coil P of the car element L energized by the circuit just traced, a certain magneto-motive-force is set up in the core of the car element L which causes a 105 certain amount of flux to pass through the primary coil P. This flux, it is believed, passes to a large extent through leakage paths which do not include the secondary coil S, so that, if this car element is bridged by an 110 active track element, the distribution of flux emanating from the leg containing the primary coil P is changed to produce a change of flux in the secondary coil S.

Operation.

115

Caution condition (speed not excessive).—Let us assume that a car equipped with the car-carried apparatus shown in Fig. 5 in its normal condition, as shown, is passing 120 through the block M when the block N next in advance is occupied by another train. Under this condition the track relay 4ⁿ is deenergized, thereby deenergizing the line relay 156 and putting the core 154 of the second track element of the pair in an open circuit. As the train moves through the block N and reaches the first track element 125

of the pair illustrated, the passage of this car element L over this track element causes a sudden increase of flux through the secondary coil S and then a sudden decrease of flux, whereby an alternating wave of electro-motive-force is generated in the secondary coil corresponding to that of a single cycle of alternating current. The secondary coil S is preferably connected in the circuit of the control relay CR in a manner so that the first wave of voltage induced therein opposes that of the voltage of the battery energizing the control relay CR, so that the control relay CR is momentarily deenergized. This cycle of alternating current voltage induced in the secondary coil S is, it is believed, due to a large extent to diversion of flux from leakage paths through the secondary coil S and to a certain extent to an increase in the total flux passing through the primary coil P. The momentary deenergization of the control relay CR permanently deenergizes this relay because its stick circuit including the front contact 171 is broken.

With the control relay CR deenergized, the repeater relay RR is deenergized, and since this repeater relay RR is also connected in a stick circuit including its own contact 180, it is permanently deenergized until restored by some other means. With the repeater relay RR deenergized, the circuit for energizing the tuning magnet TM is broken; and the time element device TE starts on its cycle of operation. Before, however, the time element device TE has operated far enough to open its contacts 162, the back contacts 207 of the repeater relay RR closes a pick-up circuit for again picking up the control relay CR which may be traced as follows:— beginning at the terminal B, wire 184, contacts 185 of the relay BR, wires 186 and 192, contacts 162 of the time element device, wires 193 and 208, back contacts 207 of the repeater relay RR, wires 209, 210 and 173, winding of the control relay CR, wire 174, secondary coil S, wire 175, back to the common return wire C. After the control relay CR has been picked up in this manner it is again in condition to maintain the brake control relay BR energized through the circuit heretofore traced, this brake control relay BR in the meantime having been held up by the circuit including the contact 162 of the time element device.

It should be remembered that at the particular stage in the cycle of operation just described the control relay CR is again picked up but the repeater relay is still in its deenergized position, the brake control relay BR being now held up by the control relay CR alone and not also by the circuit including contact 162 of the time element device. When the time element device swings in a counter-clockwise direction, the contact 163 of this device

during the last portion of its stroke contacts 65 with the stationary contact 211 and completes a pick up circuit for the repeater relay RR which may be traced as follows:— beginning at the terminal B, wire 170, front contact 171 of the control relay CR, wires 176 and 177, 70 lower winding of the relay RR, wires 178 and 212, contacts 211—163, wire 213, back to the common return wire C. Since, as has been assumed, the speed of the train is not excessive, the time element device TE will complete its cycle and return to its normal condition before the car passes by the second track element of the pair; this time element device being held in its normal position by the timing magnet TM, this magnet being energized 75 because the repeater relay RR is in its picked up position.

Assume that the train now passes over the second element of the pair of track elements, the time element device again starts from its 85 inactive position and completes a cycle of operation in the same manner as just explained without imposing a brake application.

Caution condition (speed excessive, engineer not alert).—Let us assume that the train in question passes by the first element of the pair of track elements in the block M, when the next block in advance is occupied by another train, and that the speed of the train 95 is excessive. The passage of the train by this first element initiates the time element device TE for reasons heretofore given, so that this time element device has only partly completed its cycle of operation when the car element L 100 passes over the second track element, which now has its coil open-circuited. As the car element passes over the second track element, the control relay CR is deenergized as heretofore described. Since the time element device TE has already started on its cycle of operation, the contact 162 is open and therefore deenergization of the control relay CR deenergizes the brake control relay BR, so that the front contacts 185 of this relay BR 110 open and thereby prevent the time starting magnet TM from again being energized and the control relay CR from again being picked up. The deenergization of the brake control relay BR also interrupts the stick circuit for 115 the brake applying device EPV as heretofore traced, thereby causing an automatic application of the brakes and the stopping of the train, the engineer being unable to restore the device EPV until a penalty has been inflicted which, in the present system, consists in requiring him to reduce the speed to less than 2 miles per hour.

The time element device TE and the various relays may be restored by the operation 125 of the time element restoring rack 165, which is operated in response to the energization of the electro-responsive device ED, which is

automatically energized as the speed is reduced to less than 2 miles per hour, providing the push button 224 is depressed, through the following circuit:—beginning at the terminal B, wire 214, contact 215 of the governor G, wires 216, push button contact 224, wire 217, winding of the device ED, wire 218, back to common return wire C. Energization of this device ED permits the flow of air pressure into the cylinder 67, causing the rack to be operated to the left, thereby returning the balance wheel 158 to its normal position, and completing the two following pick-up circuits:—(1) beginning at the terminal B, wire 220, contact 203, wires 221, 210 and 173, winding of the control relay CR, wire 174, secondary coil S, wire 175, back to common return wire C; and (2) wire 220, contact 203 on the rack 165, wire 222, upper winding of the repeater relay RR, wire 223, back to common return wire C. With the control relay CR and the repeater relay RR energized and the time element device TE in its normal position, the brake control relay BR is picked up, so that a pick-up circuit for the brake applying device EPV is completed as soon as the push button 224 is released and the rack 165 and its associated contact 203 has returned to its normal position providing the speed of the train is less than 2 miles per hour, which circuit comprises the normally energized circuit for the device EPV to the winding of this device from whence it comprises wires 205 and 225, contact 226 of the speed governor G, wire 227, back to the common return wire C. The completion of this circuit again picks up the brake control device EPV which is maintained energized through its stick circuit heretofore traced, so that the engineer after having been penalized in this manner may release the brakes and again proceed along the track in accordance with traffic conditions ahead. The push button 224 is used to avoid unnecessary operation of the time element restoring device every time the train stops.

Caution condition (speed excessive, engineer anticipates automatic application).—In view of the foregoing operations of the system shown in Fig. 5 as described, it is of course understood that, if the train moves at a speed to receive two successive control influences in less than a predetermined time, the relays CR, RR and BR will assume their deenergized position and the time element device TE will assume its intermediate position. Let us assume now that the engineer has moved his brake valve handle 66 to the service brake applying position before he passes a pair of spaced elements at excessive speed and the brake control relay BR is deenergized. Since, under this condition, the brake control device EPV is still up and its stick contact is still closed, an energizing circuit for this device EPV and the electrically operated valve

EV of the clockwork mechanism CM heretofore described in connection with Fig. 2 in series is completed and may be traced as follows:—beginning at the terminal B, wire 230, contacts 231—232, wire 233, winding of the device EV, wires 234 and 201, primary coil P, wire 202, contact 203 operated by the rack 165, wire 204, winding of the device EPV, wires 205 and 206, front contact 228, wire 229, back to common return wire C. Sufficient current is caused to flow in the branch including the electrically operated valve EV as distinguished from the branch including the resistance 199 by reason of the relative value of the ohmic resistances of these two branches, and the resistance 199 has been added for the purpose of dividing the current for the primary coil P and the device EPV in series between these two branches in such a way that the device EV responds when the brake valve is moved to the service position. This circuit maintains the brake applying device EPV energized and inactive and also starts the clockwork mechanism CM described in connection with Fig. 2 so as to close the contacts 85 and 235 a predetermined period of time after the brake application has been started (assumed to be 6 or 7 seconds). It is thus noted that the engineer may proceed along the track without getting an automatic brake application even though the speed restriction set up by the spacing of track elements along the track has been exceeded, providing he has anticipated such an automatic brake application by placing his brake valve in the service position and keeps it there long enough to make an effective manual application of the brakes and providing he keeps the brakes applied until the speed of the train has been reduced to 22 miles per hour as indicated by the governor G. If the engineer's brake valve has been held in the service position for the predetermined time mentioned, that is, until the contacts 85 are closed, he may move the brake valve to the lap position, whereupon a circuit is closed including the device EV and EPV and the following partial circuit:—beginning at the terminal B, wire 236, contacts 237—238, wire 239, contacts 85, wires 240 and 233.

After the speed of the train has been reduced to less than 22 miles per hour, the relays CR, RR and BR and the time element device TE may be restored to their normal condition by the depression of push button 224 which energizes the restoring electro-responsive device ED through the following circuit:—beginning at the terminal B, wire 241, contact 242 of the speed governor G, wire 243, contacts 235, wire 244, push button 224, wire 217, winding of the device ED, wire 218, back to the common return wire C. With the restoring device ED energized, the time element device and other changed parts may be

restored to its normal condition, so as to allow the train to proceed in accordance with traffic conditions ahead. It should be noted that even though the automatic brake control mechanism has been actuated no penalty (reduction of speed to less than 2 miles per hour) has been inflicted, because the engineer has anticipated the automatic brake application by a full service manual brake application.

Clear traffic conditions.—Let us assume now that the train in question passes by the pair of track elements at a speed in excess of that permitted by the spacing of these elements when the block N is occupied. Under this condition the time element device TE is initiated on its cycle of operation when the train passes by the first element for reasons heretofore given. When the car element L passes by the second track element, even though the time element device has not yet returned to its normal condition no automatic brake application takes place. This is because the second element is not capable of transmitting a control influence when its winding 154 is closed in a circuit of low resistance. One theory of reasoning by which this immunity of response of the car element by its passage over a track element having its coil closed in a circuit of low resistance may be accounted for is that the passage of a few lines of flux permeating from the element L through this second track element causes a current to be set up in this coil 154 which is in a direction to oppose a further increase in flux in this element, so that very little change of flux through the secondary coil emanating from the primary winding P takes place, and consequently very little voltage is induced in the secondary coil S. In other words, the winding 154 on the track element acts, it is believed, as a bucking coil, thereby preventing a material change of flux through the secondary coil of the car element L even though it is disposed in cooperative relation with a magnetizable core 152 of low reluctance. It is thus noted that only one control influence is transmitted from each pair of track devices under clear traffic conditions of a block so that no speed restriction is set up by these pairs of elements.

Modified penalty suppressing means.

In Fig. 6 of the drawings has been illustrated a system substantially the same as that shown in Fig. 5 (certain parts thereof being omitted) in which the penalty suppressing means includes a penalty suppressing relay PR substantially the same as that shown in Fig. 4, requiring the engineer to anticipate an automatic brake application and requiring him to keep his brake valve in the service position until the speed of the train has been reduced to, say, 22 miles per hour in order to

avoid the penalty of practically coming to a stop. In the embodiment of the invention shown in Fig. 6, if the engineer moves his brake valve to the service position, a circuit is completed for picking up the penalty suppressing relay PR which may be traced as follows:—beginning at the terminal B, wire 196, front contact 197 of the brake control relay BR, wires 198 and 234, wire 246, winding of the relay PR, wire 247, contacts 248—249, wire 250, back to common return wire C.

With the relay PR in its energized position, a stick circuit for this relay is completed as follows:—wire 251, front contact 252 of the penalty suppressing relay PR, wires 253 and 246, winding of the relay PR, wire 247, contacts 248—249, wire 250, back to common return wire C. Also, with this relay energized, another circuit for holding the device EPV in its energized position is completed which may be traced as follows:—beginning at the terminal B, wire 251, front contact 252 of the relay PR, wires 253, 234 and 201, primary coil P, wire 202, contact 203 operated by the rack 165, wire 204, winding of the EPV, wires 205 and 206, front contact 228 of the EPV, wire 229, back to the common return wire C.

It is thus noted that the train may proceed along the track without the imposition of an automatic brake application even though the speed set up by the spaced track elements is exceeded under caution traffic conditions, providing the engineer has anticipated such an application by initiating a manual application. After the speed of the train has been reduced to 22 miles per hour under the conditions just mentioned, the time-distance brake applying mechanism may be restored to its normal condition by the engineer's operation of the push button 224, by reason of which the following circuit is completed:—beginning at the terminal B, wire 254, front contact 255, of the relay PR, wire 256, contact 242, of the governor G, wire 244, push button contact 224, wire 217, winding of the device ED, wire 218, back to common return wire C. The completion of this circuit returns the time-distance interval brake applying mechanism to its normal position, thereby permitting the train to proceed in accordance with traffic conditions ahead as soon as the rack returns to its normal position.

While several specific forms of the invention have been shown and described, and the invention has been applied to speed control systems both the continuous inductive control type and the intermittent inductive control type based on the time-distance interval principle, in each form the primary purpose is to stimulate and maintain vigilance on the part of the engineer, and requiring him under penalty of being obliged to stop in order to proceed, to recognize and observe the indications of the block signals, particularly the

caution signal. The engineer is penalized if he does not control his train properly and in accordance with the indications of wayside signals. In each of the systems described 5 means is provided for suppressing the penalty ordinarily inflicted upon the engineer providing he has initiated a manual application of the brakes before an automatic brake application is initiated. Various penalty 10 suppressing means have been provided for suppressing the penalty in accordance with various degrees of refinement. The first one of these permits the engineer, after initiating the brake application, to put the engineer's 15 brake valve back into the lap position, whereby excessive venting of the brake pipe is prevented. This is desirable, so that a corresponding small amount of air pressure only need be pumped into the brake pipe when 20 the brakes are again released. In the second mentioned penalty suppressing means the engineer is required to keep his brake valve in the service position permanently until the speed of the train has been reduced to a safe 25 value, which has been taken at 22 miles per hour.

Having thus shown and described several embodiments of the invention as applied to several different types of train control systems, the specific disclosures made have been 30 shown to illustrate the nature of the invention rather than its scope, and it is desired to be understood that various changes and modifications may be made to adapt the invention to various other types of systems without departing from the spirit of the invention or the idea of means underlying the same.

What I desire to secure by Letters Patent 40 of the United States is:—

1. In an automatic train control system, the combination of means on the train for applying the brakes in the usual air brake system, means for setting up permissive speed 45 limits for the train, penalty means if effective requiring the train to be stopped each time the brakes are automatically applied before the brakes can be released, and means including a time element device superimposed upon said usual air brake system for preventing said penalty means from becoming effective and active if and only if the brake valve is in the service position or has been there at least long enough to cause a pre-determined degree of brake application since 55 the last time the train brakes have been released.

2. In an automatic train control system, the combination with the usual air brake system including means for applying the brakes manually, means for setting up permissive speed limits for the train, means for inflicting a penalty, and means for preventing the infliction of such penalty comprising 60 a time measuring device operatively connect-

ed to the engineer's brake valve and effective if and only if the brake valve is in the service position or has been there a period of time equal to or more than that necessary to cause a predetermined reduction in the equalizing 70 reservoir pressure of said air brake system and has not thereafter been moved to a brake releasing position.

3. An automatic train control system comprising, an automatic brake applying device 75 superimposed on the usual type of air brake system including the usual charged brake pipe, means for automatically actuating said device if predetermined speed limits are exceeded, means for penalizing the engineer if 80 similar speed limits are exceeded, and means for preventing the infliction of a penalty by said last mentioned means including a time element device operatively connected to the engineer's brake valve of said system effective 85 if the engineer's brake valve has been in the brake applying position for a period of time corresponding to the time necessary to initiate an adequate brake application and has not been returned to the brake releasing position thereafter.

4. In an automatic train control system, the combination of means for automatically applying the brakes of the usual air brake system of a train, and means for preventing 90 such an automatic brake application including a time element device separate and distinct from the air brake system itself but governed by the engineer's brake valve which is effective to prevent such brake application 95 a predetermined time after said time element device has been initiated and providing the engineer's brake valve has not thereafter been moved to the running or release position, and means for initiating said time element device 100 effective if and only if the engineer's brake valve is in the brake applying position.

5. In an automatic train control system, the combination of means for automatically applying the brakes of the train if the speed of 110 the train is excessive, means for penalizing the engineer if the speed of the train is excessive, and means including a time element device in addition to the usual air brake system governed by the engineer's brake valve 115 for suppressing operation of said penalizing means effective if and only if the usual engineer's brake valve is in the brake applying position or has been in such position for a pre-determined time and has thereafter not been 120 moved toward the brake releasing position beyond the lap position.

6. In an automatic train control system of the time-distance interval type, the combination of a normally energized and normally inactive brake applying device, a penalty inflicting device, means partly on the trackway and partly on the vehicle for transmitting control influence to the car-carried apparatus and including trackway devices spaced in accord- 125 130

ance with the speed limit imposed at such point under predetermined traffic conditions ahead, means for deenergizing said brake control device and placing said penalty inflicting device in its active condition if two successive control influences are received in less than a predetermined time, and means for preventing said penalty inflicting device becoming active including a time measuring device controlled by contacts on the engineer's brake valve, said last mentioned means being effective if and only if the engineer's brake valve is in the brake applying position or has been moved to such position and has remained there for a predetermined time and has not thereafter been returned beyond the lap position.

7. An automatic train control system comprising, a normally energized and normally inactive brake control device, means for automatically actuating said brake control device if the speed of the train exceeds predetermined speed limits, a penalty inflicting device for inflicting a penalty if the speed of the train is excessive, and means for suppressing functioning of said penalty inflicting device including contacts closed when the engineer's brake valve is in a brake applying position and effective only if placed in such position before the speed of the train is excessive and is kept in such position for a predetermined period of time or until the speed is no longer excessive.

8. An automatic train control system comprising penalizing means for penalizing the engineer if the speed of the train is excessive, penalty suppressing means normally in its inactive condition, and means effective to place such penalty suppressing means in its active condition effective if and only if the engineer's brake valve is placed in its brake applying position prior to the time of exceeding such speed limit and is kept in such position for a predetermined period of time or until the speed is no longer excessive.

9. An automatic train control system comprising, a braking system including a train pipe and an engineer's brake valve which valve must be placed in the brake applying position for a certain period of time and thereafter not be moved to the brake releasing position in order to effect a brake application of a predetermined degree, a brake control device automatically operable which if operated effects a brake application, a time element device, and means for penalizing the engineer if said brake control device is operated automatically unless the engineer's brake valve is in its brake applying position or has been there for a predetermined period of time as manifested by said time element device and has not thereafter been moved to the release position.

10. An automatic train control system for railway trains equipped with an air brake

system including a train pipe and an engineer's brake valve in which the engineer's brake valve must be placed in the brake applying position for a certain period of time and must thereafter not be moved to the brake releasing position in order to effect and hold a brake application of a predetermined degree, a time element device for ascertaining if said brake valve has been in the brake applying position for said certain period of time and has not thereafter been moved to the brake releasing position, an automatically operable brake control device operated in accordance with traffic conditions ahead, and means for penalizing the engineer if said brake control device is operated unless a manual brake application was initiated which ultimately became effective as manifested by the condition of said time element device.

11. An automatic train control system for railway trains equipped with a brake system including a normally charged brake pipe which if vented to a predetermined extent effects a brake application and including an engineer's brake valve which must be placed in the brake applying position for a predetermined period of time and not thereafter moved to a brake releasing position in order to initiate and hold a full service brake application, a brake applying mechanism operable to effect a brake application automatically under adverse traffic conditions ahead, a time element device for determining if the engineer's brake valve has been moved to effect a full service brake application, and means for penalizing the engineer if said brake applying mechanism is operated when no manual brake application has been initiated as determined by said time element device.

12. An automatic train control system for railway trains equipped with a braking system including a normally charged brake pipe which is vented to a predetermined extent effects a brake application and including an engineer's brake valve which must be placed in the brake applying position for a predetermined period of time and not thereafter be moved to a brake releasing position in order to initiate and hold a full service brake application, a brake applying mechanism operable to effect a brake application automatically under adverse traffic conditions ahead, means for penalizing the engineer if said brake applying mechanism is operated automatically, a time element device effective to prevent said brake applying mechanism from being operated automatically if the engineer's brake valve has previously been operated to the brake applying position and is held there for a predetermined time and has not thereafter been moved to a brake releasing position.

13. An automatic train control system for railway trains equipped with a braking system including a normally charged brake pipe

- which if vented to a predetermined extent effects a brake application and including an engineer's brake valve which must be placed in the brake applying position for a predetermined period of time and not thereafter be moved to a brake releasing position in order to initiate and hold a full service brake application, a normally energized electro-responsive device connected in a stick circuit 10 which if deenergized effects a brake application, a contact in said circuit controlled in accordance with traffic conditions ahead, and means including a time retarded device which closes a multiple branch circuit around said contact if the engineer's brake valve is in the brake applying position or has been in such position for such predetermined period of time and has not thereafter been moved to a brake releasing position provided said double-heading cock has not been moved to a double-heading position. 70
- 15 17. Car-carried apparatus for automatic train control systems comprising, an engineer's brake valve movable to a brake applying position and a lap position, an electrically operable brake control device connected in a stick circuit, electrically operable means of the stick type for maintaining said stick circuit closed, a pick-up circuit for said electrically operable means including a contact closed if the engineer's brake valve is in the brake applying position, and a contact in the stick circuit of said electrically operable means closed if the engineer's brake valve is in the lap position. 75
- 20 18. Car-carried apparatus for automatic train control systems comprising, an engineer's brake valve movable to a brake applying position and a lap position, an electrically operable brake control device connected in a stick circuit, electrically operable means of the stick type for maintaining said stick circuit closed, a pick-up circuit for said electrically operable means including a contact closed if the engineer's brake valve is in the brake applying position, and a contact in the stick circuit of said electrically operable means closed if the engineer's brake valve is in the lap position. 80
- 25 19. Car-carried apparatus for automatic train control systems comprising, an engineer's brake valve movable to a brake applying position and a lap position, an electrically operable brake control device connected in a stick circuit, electrically operable means of the stick type for maintaining said stick circuit closed, a pick-up circuit for said electrically operable means including a contact closed if the engineer's brake valve is in the brake applying position, a contact in the stick circuit of said electrically operable means closed if the engineer's brake valve is in the lap position, and means for preventing said electrically operable means from assuming a position in which its stick circuit may be 90 closed even though it is energized until the expiration of a predetermined period of time. 95
- 30 20. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 100
- 35 21. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 105
- 40 22. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 110
- 45 23. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 115
- 50 24. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 120
- 55 25. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 125
- 60 26. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 130
- 65 27. An automatic train control system comprising, the usual railway air brake system, including the usual charged brake pipe, the usual engineer's brake valve and the usual cut-out cock in the pipe connecting the brake valve and the brake pipe, a normally energized brake control device, means for automatically deenergizing said brake control device including means partly on the vehicle and partly along the trackway and governed in accordance with traffic conditions ahead, 135

- which if vented to a predetermined extent effects a brake application and including an engineer's brake valve which must be placed in the brake applying position for a predetermined period of time and not thereafter be moved to the brake releasing position in order to initiate and hold a full service brake application, brake applying mechanism of the type which if once in its active condition will 10 remain in such condition until restored by separate means, automatic means for controlling said brake applying mechanism in accordance with traffic conditions ahead of the train, a time element device effective to prevent 15 the brake applying mechanism from being operated by the automatic means if the engineer's brake is in the brake applying position or has been placed in such position and held there for said predetermined period of 20 time and has not thereafter been moved to a brake releasing position, and means for restoring said brake applying mechanism to normal effective only if the speed of the train is reduced to an extremely low value.
- 25 21. Means for determining when a predetermined degree of brake application has been initiated or is effective in an air brake system of the type in which the brake pipe is normally charged and which if vented 30 permits air to flow from an auxiliary reservoir into a brake cylinder until the pressure in said auxiliary reservoir has fallen to the same value as that existing in the brake pipe, and in which an equalizing reservoir 35 and an equalizing discharge piston valve are provided, whereby if pressure is vented from said equalizing reservoir said equalizing discharge piston valve will vent air from said brake pipe until the brake pipe pressure has 40 dropped to the pressure existing in said equalizing reservoir comprising; time controlled indicating means for indicating when a brake application of a predetermined degree has been effected, means for operating 45 said indicating means to its indicating condition when said equalizing reservoir has been vented through a restricted opening for a predetermined interval of time, means for maintaining said indicating means in its indicating condition so long as said brake pipe 50 has thereafter not been recharged, and means for preventing venting of said equalizing reservoir through said restricted opening when said indicating means is in its indicating condition.
- 55 22. Means for determining when a predetermined degree of brake application has been initiated or is effective in an air brake system of the type in which the brake pipe is 60 normally charged and which if vented permits air to flow from an auxiliary reservoir into a brake cylinder until the pressure in said auxiliary reservoir has fallen to the same value as that existing in the brake pipe, and in which an equalizing reservoir and an

equalizing discharge piston valve are provided, whereby if pressure is vented from said equalizing reservoir said equalizing discharge piston valve will vent air from said brake pipe until the brake pipe pressure has 70 dropped to the pressure existing in said equalizing reservoir comprising; electro-responsive means which if energized manifests that a brake application of a predetermined degree has been initiated, time controlled 75 means for energizing said electro-responsive means when said equalizing reservoir has been vented through a restricted opening for a predetermined interval of time, and means for maintaining said electro-responsive 80 means in its energized condition until said brake pipe is recharged.

23. Means for determining when a predetermined degree of brake application has been initiated or is effective in an air brake 85 system of the type in which the brake pipe is normally charged and which if vented permits air to flow from an auxiliary reservoir into a brake cylinder until the pressure in said auxiliary reservoir has fallen to the same 90 value as that existing in the brake pipe, and in which an equalizing reservoir and an equalizing discharge piston valve are provided, whereby if pressure is vented from said equalizing reservoir said equalizing discharge piston valve will vent air from said brake pipe until the brake pipe pressure has dropped to the pressure existing in said equalizing reservoir comprising; electro-responsive stick 95 means which if energized manifests that a 100 brake application of a predetermined degree has been initiated, means for energizing the pick-up circuit of said electro-responsive means when said equalizing reservoir has been vented through a restricted opening for a predetermined interval of time, and means for closing a stick circuit for said electro-responsive means to maintain it in its energized condition so long as said brake pipe 105 has thereafter not been recharged.

110 24. In an air brake system of the usual construction including a normally charged brake pipe, an equalizing reservoir, and an engineer's brake valve having a brake applying position, a brake releasing position 115 and a lap position, and wherein the equalizing reservoir is vented through a restricted opening when the brake valve is in said brake applying position, the combination with a stick electro-responsive device for manifesting when a predetermined degree of brake application has been initiated or is effective having a pick-up circuit and a stick circuit, means for closing said pickup circuit when 120 said engineer's brake valve has been in said brake applying position for a predetermined period of time, and a contact in said stick circuit closed when said brake valve is in the lap position.

125 25. An automatic train control system com- 130

prising, a brake control device, a permissive speed device, an actual speed device, means for actuating said brake control device if the actual speed exceeds the permissive speed, means for restoring said brake control device effective only after a penalty has been inflicted, and another means for restoring said brake control device to normal effective if

and only if the engineer has placed the brake valve in the brake applying position before 10 the brake control device was actuated and has kept it there for a predetermined period of time.

In testimony whereof I hereby affix my signature.

FRANK L. DODGSON.
